Application May 20, 1954, Serial No. 431,124

9 Claims. (Cl. 201—55)

This invention relates to variable resistors of the type employed in radio and television receivers and has as its purpose to provide a control of this character especially adapted for use with high voltages. The advent of so-called color television has created a demand for low cost variable resistors capable of handling voltages on the order of 15,000 volts above ground and 5,000 volts across the end terminals of the resistor. These voltages are much greater than those safely handled by variable resistors now employed in radio and ordinary black and white television receivers.

Those skilled in this art will readily appreciate that voltages of this magnitude create a difficult problem in insulation; and this problem is greatly aggravated if the size of the control is limited. Heretofore demands for variable resistors capable of handling high voltages were generally met without regard for the over-all size of the control. Practically the only factor determining the design of such controls was the obtention of adequate insulation to assure against electrical breakdown. Thus it was common practice in the past to employ a relatively large molded housing and to arrange the resistance element as a curled strip extending along the inside surface of the cylindrical side wall of the housing. This arrangement provided maximum space between the resistance element and the grounded control shaft and also between the resistance element and the collector ring of the center terminal.

A curled resistance strip, however, does not lend itself to size reduction. Accordingly, the solution of the problem of providing a variable resistor which is capable of handling high voltages and still can satisfy the requirements of set manufacturers for reduction in over-all size compelled abandonment of the curled resistance element and the substitution of the familiar flat arcuate split ring shaped resistance element which lies flat against the base. Moreover, the flat arcuate element is better suited to production methods of manufacture and hence enables desirable cost reduction. But a flat arcuate resistance element reintroduces the problem of maintaining adequate electrical spacing between the element and the center collector ring and the grounded shaft at least if the over-all size of the control is to be kept within the limits prescribed by set manufacturers. The present invention solves this problem in an entirely satisfactory manner by mounting and driving the contactor of the control in a novel way.

More specifically this invention provides a so-called high voltage variable resistor which is so designed and constructed that adequate electrical spacing between its resistance element and collector ring is made possible by a new and novel off center disposition of the contactor which allows its collector ring engaging contact fingers or paddles to travel in an orbit closely adjacent to the axis of the control while its resistance element engaging contact fingers travel in an orbit spaced a substantial distance radially out from the axis.

Where the housing of the control is formed in the fa-

2

miliar way by a cup-shaped metal cover joined at its edge to the base of insulating material upon which the resistance element is fixed, the resistance element should be spaced from the cylindrical side wall of the cover a distance about as great as its shortest distance from the collector ring. This positional relationship utilizes the available space to achieve maximum electrical clearance between the resistance element and both the cover and the collector ring, but to attain this desirable condition within a cover of relatively small diameter requires that the collector ring be much smaller in diameter than has heretofore been customary. This in itself, would present no serious difficulty, but when coupled with the desire to use a contactor like that shown in Patent No. Re. 23,750, and which years of experience has proven to be highly satisfactory, a problem was encountered.

The solution of this problem is another object of this invention; and it resides in an extremely eccentric disposition of the contactor so that its spring contact fingers or paddles which ride upon the collector ring lie at the same side of the axis of rotation as the contact fingers or paddles which ride upon the resistance element, together with a novel mounting for the contactor assembly by which it is securely held against any possible rocking and smooth balanced operation of the control is assured.

In instances where the actuating shaft of the control is metal, this invention further contemplates an improved driving connection between the shaft and the contactor which not only assures stability for the contactor, but also maximum insulation between the contactor and the grounded shaft.

A further object of this invention is to provide a resistor of the character described which is so designed and constructed as to lend itself readily to the incorporation of adequate insulating barriers between the portions of the control which operate at maximum potential difference.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate several complete examples of the physical embodiments of the invention constructed according to the best modes so far devised for the practical application of the principles thereof, and in which:

50 Figure 1 is a longitudinal sectional view through a variable resistor embodying one adaptation of this invention;

Figure 2 is a perspective view illustrating the interior of the housing of the control, the base and contactor assembly being removed therefrom;

55 Figure 3 is a perspective view of the base and contactor assembly shown separated, and illustrating the inside aspect of the base with the resistance element and collector ring mounted thereon;

Figure 4 is a perspective view illustrating the inside aspect of a base suitable for use in the control shown in Figure 1, but provided with additional insulating barriers to be disposed between the resistance element and the side wall of the metal housing or cover;

Figure 5 is a cross sectional view through Figure 4 on the plane of line 5—5;

Figure 6 is a longitudinal sectional view through a variable resistor illustrating another adaptation of this invention;

70 Figure 7 is a perspective view of the inside of the metal cover which forms part of the housing of that embodiment of the invention shown in Figure 6;

Figure 8 is an exploded perspective view of the other parts of the control shown in Figure 6;

Figure 9 is a longitudinal sectional view through a variable resistor illustrating another embodiment of this invention;

Figure 10 is a perspective view of the base and contactor assembly of the resistor shown in Figure 9;

Figure 11 is a perspective view illustrating the interior of the cover of the resistor shown in Figure 9, with the contactor drive arm in position therein;

Figure 12 is a longitudinal sectional view through a variable resistor illustrating still another modification of this invention;

Figure 13 is a perspective view of the interior of the cover of that form of the invention shown in Figure 12 and illustrating the contactor assembly in position therein;

Figure 14 is a perspective view of the inside aspect of the base of the resistor shown in Figure 12.

Referring now to the accompanying drawings and especially to Figures 1, 2 and 3, the numeral 5 designates the base of the variable resistor which as is customary, is round and may be stamped from suitable sheet insulation. A flat arcuate, split-ring shaped resistance element 6 is attached or painted on one side of the base. Where the resistance element is a separate piece as shown, it is held in place by terminals 7 secured to the base with portions thereof clinched over the ends of the resistance element and other portions projecting through the base to provide for the attachment of conductor leads thereto.

The base also has a collector ring 8 seated thereon coaxially with and inside the arcuate resistance element. The collector ring is held in position by a center terminal 9 which extends therefrom and passes out through the base as shown.

A cup-shaped metal cover 10 preferably formed as a stamping, coacts with the base to provide a housing for the instrumentalities of the control. The cover has a flat bottom or end wall 11 and a cylindrical side wall 12, secured to the peripheral portion of the base in the customary manner with the end wall 11 over that side of the base at which the resistance element and collector ring are located. A combined bearing and mounting bushing 13 is fixed to the end wall 11 in coaxial alignment, and journaled in this bushing is a shaft 14 by which the rotatable contactor assembly of the control, indicated generally by the numeral 15, may be driven.

The contactor assembly comprises a stamped and formed contactor 16, of the type shown for instance in Patent No. Re. 23,750. The contactor thus has two sets of spring contact fingers or paddles 19 and 20, one to traverse the collector ring and the other to ride upon the resistance element, and a pair of ears 18 by which the contactor is fixed to a carrier 17. The carrier is a flat substantially rectangular piece of stiff insulating material.

The driving connection between the shaft 14 and the contactor assembly comprises a stiff arm 21 stamped from sheet metal and fixed to the inner end of the shaft in an off-center relationship so that one end portion of the arm extends considerably farther from the shaft than the other. The extremities of the arm are bent up to provide a pair of opposite flat driving lugs 23 flanked by supporting shoulders 24. All of the supporting shoulders 24 lie in a common plane normal to the shaft axis, and the driving lugs 23 are substantially parallel to one another and to the shaft axis to fit snugly into slots 25 in the opposite end portions of the carrier 17.

In order to assure a satisfactory driving connection between the arm 21 and the insulated carrier 17 the driving lugs 23 are a bit longer than the thickness of the carrier so that when the carrier is seated upon the shoulders 24 the extremities of the lugs protrude slightly above the face of the carrier at which the contactor is located. This brings the driving lugs, which of course

are at ground potential, into close proximity to the contactor and also the resistance element and collector ring, but an insulating shield 26 of suitably high dielectric strength affords the necessary insulation. This shield 5 consists of a piece of relatively flexible high dielectric insulating material clamped between the contactor and its carrier with the attaching ears 18 of the contactor received in notches in opposite edges of the shield.

The end thrust imposed upon the contactor assembly 10 and the drive arm by the reaction of the spring contact fingers against the resistance element and the collector ring is carried by the inner rolled end 27 of the bushing 13 against which the adjacent rear face of the arm 21 bears. A conventional C washer 28 holds the shaft against 15 inward axial displacement.

For strength and stiffness the arm 21 is preferably channel shaped in cross section; and to define the limits of rotation of the contactor assembly the longest end of the arm 21 is shaped to provide opposite radially disposed edges 29 which coact with stop abutments 30.

The mounting of the control upon a supporting panel (not shown) is accomplished in the customary manner by a clamping nut threaded on the bushing 13, and to hold the control against turning a lug 31 projects from 25 the end wall 11 of the cover to coact with suitable abutments on the panel, not shown.

Attention is directed to the fact that the resistance element is spaced radially from the cylindrical side wall 12 of the metal cover or housing unit a distance which is 30 almost as great as the shortest distance between the resistance element and the collector ring 8. This positional relationship utilizes the space available to achieve maximum electrical spacing between the grounded cover and the resistance element and also between the resistance element and the collector ring, but to gain this desired electrical spacing between the resistance element and the collector ring requires that the collector ring be much smaller in diameter than has heretofore been the practice. To allow such reduction in diameter of the 35 collector ring and still enable the use of the described contactor which experience has shown to be very satisfactory, is one of the accomplishments of this invention.

The unusual extremely eccentric position of the contactor and its carrier with respect to the shaft and the manner in which the carrier is connected with the control shaft makes it possible to achieve this desired result. By this expedient the contact portions of the spring fingers or paddles 19 travel in orbits very close to the shaft axis while the contact portions of the fingers or paddles 20 travel in orbits quite a distance out from the shaft axis. In fact, the diameters of the orbits of the paddles 19 are but slightly greater than the diameter of the shaft itself, while the orbits of the paddles 20 are out approximately two-thirds the distance from the shaft axis to the side wall of the housing.

However, it is not enough that the contactor assembly be arranged in this off center fashion, for to assure smooth, satisfactory operation, it is also necessary that the mounting of the contactor assembly be such that it will be securely held against rocking. This requirement is met by the specific construction of the shaft-carried arm 21 and the manner in which it is drivingly connected to the carrier 17.

If greater assurance against flash over between the resistance element and the grounded metal side wall of the housing is necessary it is easily obtained in the control shown in Figures 1, 2 and 3, by the addition of annular flanges 32 on the inner face of the base as shown, for instance, in Figures 4 and 5. These flanges provide insulating barriers lying between the resistance element and the side wall 12 of the cover.

In that form of the invention shown in Figures 6 to 8 inclusive, no part of the inside wall of the housing is metal. To this end, the base 5' of the control has a cy-

cylindrical side wall 35 formed integrally therewith, and a disc 36 of insulating material covers the inside face of the metal end wall 11'. This disc is held in place by being confined between the edge of the side wall 35 and an annular bead 37 in the end wall 11'. The metal cover 10' fits over the molded base unit with its side wall 12' encircling the side wall 35. In keeping with the increased assurance against electrical breakdown afforded by this construction the base 5' has an insulating barrier 38 formed integrally therewith and lying between the resistance element 6' and the collector ring 8'. Though the resistance element is secured in place by its terminals 7' in the same way as previously described it should be noted that the element lies closer to the side wall of the housing thus enabling a reduction in the size of the unit.

In addition, the contactor assembly of this form of the invention is different from that of Figures 1 to 3 inclusive, the chief distinction being in the fact that the carrier 17' and the operating shaft 14' are one integral molding of suitable insulating material. The contactor 16 is mounted directly on the carrier, but with this difference namely, that both sets of spring fingers or paddles 19 and 20 lie at the same side of the shaft axis. Hence, the off-center disposition of the contactor is even greater in this form of the invention than it is in the construction shown in Figures 1 to 3 inclusive.

Mounting of the collector ring 8' is also somewhat different in that in this case it rests directly on a central annular boss 41, and thereby obviates the legs by which the collector ring 8' is held at its proper elevation.

To provide the necessary smooth running thrust bearing to carry the end thrust imposed upon the rotatable assembly by the spring tension of the contact fingers the carrier 17' has a hub 39 formed thereon which bears against the adjacent face of the insulating disc 36; and the limits of rotation of the contactor assembly are defined by a stop lug 40 formed integrally with the side wall 35 and with which the opposite side edges of the carrier 17' engage.

The embodiment of the invention shown in Figures 9, 10 and 11, is quite similar to that shown in Figures 1, 2 and 3, and differs therefrom principally in the manner in which the contactor 16 is mounted and driven. Thus, the contactor, which is identical to the one previously described and hence like that of Patent No. Re. 23,750, is mounted upon and fixed to a carrier 41 by means of the ears or tabs 18. The carrier is a flat piece of stiff insulating material shaped as a segment of a circle encompassing an area slightly greater than a semi-circle. The radius of the arcuate edge of the carrier is but slightly less than the inside diameter of the metal cover 10 so that the carrier provides an effective insulating barrier between the contactor and the bottom wall 11 of the cover and also between the contactor and a metal driving member 42 which is fixed to the shaft 14 inside the cover and upon which the carrier is mounted.

The driving member 42 is a stiff T-shaped metal stamping fixed to the drive shaft 14 at the junction of the head and stem of the T, so that the driving member provides three arms radiating from the shaft. The extremities of the diametrically opposite arms provided by the head or cross bar of the T are formed to have a pair of opposite flat driving lugs 43 projecting up from adjacent carrier supporting surfaces 44; and the extremity of the third arm or stem of the T is formed to provide a third carrier supporting surface 45. All of these carrier supporting surfaces lie in a common plane normal to the shaft axis, and the driving lugs 43 are substantially parallel to one another and to the shaft axis to fit snugly in diametrically opposite notches 46 in the periphery of the insulating carrier 41. Hence the cross bar of the T-shaped drive arm is substantially parallel to the straight edge of the carrier and the stem portion of the T extends toward the circular edge of said carrier.

To assure a satisfactory driving connection between the T-shaped driving member and the carrier, the driving lugs 43 are slightly longer than the thickness of the carrier so that when the carrier is seated upon its supports 44 and 45, the extremities of the driving lugs protrude beyond the face of the carrier at which the contactor is located. However, it should be noted that because of the size of the carrier, the protruding ends of the driving lugs 43 are spaced a substantial distance from the ears or tabs 18 by which the contactor is fixed to the carrier.

The end thrust imposed upon the contactor assembly and the drive arm by the reaction of the contactor fingers against the resistance element and the collector ring is carried by the inner rolled end 27 of the bearing and mounting bushing 13 against which the adjacent rear face of the drive arm bears, the drive shaft being held against inward axial displacement by the conventional C washer 28 as in the Figure 1 embodiment of the invention.

To define the limits of rotation of the contactor assembly, the stem portion of the T-shaped driving member is shaped to provide opposite radially disposed edges 47 which coact with stop abutments 48 sheared and formed inwardly from the end wall 11 of the metal cover. The mounting of the control upon a supporting panel is accomplished in the customary manner by a clamping nut threaded onto the bushing 13, and to hold the control against rotational displacement after mounting, a lug 49 may be sheared and formed outwardly from the end wall of the metal cover to coact with suitable abutments 30 on the panel.

It will be noted that as in the Figure 1 construction the resistance element 6 is spaced from the cylindrical side wall 12 of the metal cover a distance which is almost as great as the shortest distance between the resistance element and the collector ring 8. This positional relationship again utilizes the space available to achieve maximum electrical clearance between the cover and the resistance element, and also between the resistance element and the collector ring, which as explained before, is much smaller in diameter than has heretofore been customary. To accommodate this reduction in diameter of the collector ring and still use the previously described highly satisfactory contactor, the contactor has been placed in an extremely eccentric position with respect to the drive shaft so that both sets of its spring contact fingers 19 and 20 lie at the same side of the shaft axis with their extremities encompassed by an area which lies inside of and is substantially equispaced from the three supports 44 and 45 upon which the carrier rests. This three point support for the contact carrier thus carries the thrust of the contact fingers in a manner which assures against rocking of the contactor and achieves well balanced smooth operation for the control.

In the embodiment of the invention shown in Figures 12, 13 and 14, the shaft 14' and the contactor drive arm 17' are parts of a unitary molding of suitable insulating material as in that form of the invention shown in Figures 6, 7 and 8, and the contactor 16 is secured to the drive arm 17' by having its ears or tabs 18 received in notches in the sides of the arm and clinched thereover. Both sets of spring contact fingers lie at the same side of the shaft axis in position to traverse the resistance element and the collector ring, and the end thrust imposed upon the contactor assembly by the spring contact fingers is carried to the end wall 11 of the cover by a relatively small diameter hub 39' on the back of the drive arm 17'.

Assurance against rocking of the contactor assembly is obtained in this construction through the use of two side thrust bearings 50 and 51. The bearing 50 is extruded from the back wall 11 of the cover and receives the shaft 14', while the bearing 51 is a hole in the base 5 which receives a trunnion 52 formed as an integral part of the arm 17' coaxially with the shaft. Obviously, of course, the bearings 50 and 51 must be exactly coaxial.

The limits of rotation of the contactor assembly are

defined by a stop 53 struck in from the end wall 11 in position to be engaged by the side edge portions 54 of the driving member 17; and outwardly struck ears or tabs 55 project from the front face of the wall 11 to provide means for mounting the resistor upon a panel.

From the foregoing description taken in connection with the accompanying drawings it will be readily apparent to those skilled in this art that this invention provides a variable resistor which not only is capable of handling exceptionally high voltages, but by virtue of its novel design and construction achieves an entirely unprecedented reduction in size for controls of this type and enables the control to be made with relatively inexpensive production methods.

What we claim as our invention is:

1. In a variable resistor having a base of insulating material, a flat arcuate resistance element on one side of the base, a collector ring on the same side of the base concentrically surrounded by the arcuate resistance element, and a contactor having spring contact fingers to traverse the resistance element and the collector ring, means for mounting and driving the contactor, comprising: a shaft constrained to rotation about an axis perpendicular to the base and concentric to the resistance element and the collector ring; a driving member fixed to the shaft and having arms radiating therefrom; supporting surfaces on the outer ends of said arms facing the base and lying in a plane normal to the shaft axis; an insulated contactor carrier seated near its periphery on said supporting surfaces; torque transmitting driving lugs on the driving member engaging in openings in the contact carrier; and means securing the contactor to the side of its carrier which faces the base with its contact fingers in position to traverse the resistance element and the collector ring and with the extremities of all of its contact fingers lying closer to the shaft axis than do said supporting surfaces on the driving member.

2. In a variable resistor, the structure set forth in claim 1 further characterized by the fact that the securing of the contactor to its carrier so disposes the same thereon that the extremities of all of its spring contact fingers lie at the same side of the shaft axis.

3. In a variable resistor, the structure set forth in claim 1 further characterized by the fact that the driving member is a stiff T-shaped metal stamping having two diametrically opposite arms and a third arm substantially at right angles to said diametrically opposite arms; supporting surfaces on the extremities of said three arms substantially spaced from the shaft axis, facing the base and lying in a plane normal to the shaft axis to provide a three point support for the contactor carrier; and further characterized by the fact that the extremities of the spring contact fingers lie in an area disposed within and substantially spaced from said three supporting surfaces.

4. In a variable resistor, the structure set forth in claim 3 further characterized by the fact that said torque transmitting driving lugs are on the extremities of the diametrically opposite arms of the drive member; and that the openings in the contactor carrier in which said lugs are received are notches in the peripheral edge portion of the carrier.

5. A variable resistor of the type wherein a stator assembly and a rotor assembly are contained within a housing having opposite end walls, the stator assembly comprising a flat arcuate resistance element and concentrically therewith, a center terminal collector ring, both on one of the end walls of the housing, and the rotor assembly including an operating shaft journaled in a bearing in the other end wall of the housing concentrically with the resistance element, characterized by the fact that the rotor assembly further comprises a contactor carrier of insulating material; a metal driving member fixed to the shaft and having arms extending therefrom in a plane normal to the shaft; supporting surfaces on the outer ends of the arms facing the stator assembly 75

and bearing against the contact carrier; torque transmitting driving lugs on the metal driving member engaging in openings in the contact carrier; and a bridging contactor affixed to the contactor carrier, said bridging contactor having spring fingers with contact pads on the outer ends thereof positioned to traverse the resistance element and the collector ring, all of the spring contact fingers lying closer to the axis of the operating shaft than to said supporting surfaces and torque transmitting driving lugs so as to assure good electrical clearance between the contact fingers and the driving lugs.

6. A variable resistor especially adapted for use with high voltage comprising: a base of insulating material; a flat arcuate resistance element on one side of the base; 15 a flat center terminal connector ring on said side of the base inside and concentric with the arcuate resistance element but spaced therefrom a distance sufficient to prevent flashover between the resistance element and collector ring at the voltages for which the resistor is designed; a housing for the instrumentalities of the variable resistor, said housing comprising the base and a stamped metal cover inverted over and secured to the base with its end wall overlying the side of the base at which the resistance element and collector ring are located; an 20 operating shaft for the resistor journaled in a bearing carried by the end wall of the metal cover and concentrically disposed with respect to the arcuate resistance element and the collector ring; and a rotatable contactor assembly within the housing driven by said shaft and comprising an insulated contact carrier consisting of a flat piece of insulating material, a contactor fixed to said piece of insulating material and having a spring contact finger to ride upon the resistance element and another spring contact finger to ride upon the collector ring, and 25 means connecting said piece of insulating material to the shaft comprising a metal arm fixed to the shaft and projecting radially in opposite directions therefrom, torque transmitting driving lugs extending from the opposite ends of the arm parallel to the shaft axis and toward the base, supporting shoulders on said arm flanking each of said torque transmitting driving lugs and facing the base, all of said supporting shoulders lying in a common 30 plane normal to the shaft axis, said torque transmitting driving lugs being readily removably received in close fitting openings in the flat piece of insulating material and thereby so positioning the contact carrier with respect to the shaft, that its spring contact fingers are correctly aligned with the resistance element and collector ring, the reaction of the spring fingers against the resistance element and collector ring holding the piece of insulating material against the supporting shoulders to thereby establish and maintain a predetermined contact pressure.

7. The variable resistor of claim 6 further characterized by the fact that the contact portions of both of said spring fingers of the contactor are disposed at the same side of the shaft axis.

8. The variable resistor of claim 6 further characterized by the fact that the contact carrier comprises a substantially rectangular flat piece of insulating material having slots in its end portions, the contactor being a sheet metal stamping and being secured to the substantially rectangular piece of insulating material and overlying one side thereof, an insulating shield interposed between the contactor and the piece of insulating material and substantially covering the entire area of the latter so as to overlie the slots in its opposite end portions; and further characterized by the fact that the connection between the shaft and the carrier comprises a stamped metal arm fixed to the shaft and having opposite end portions extending in opposite directions from the shaft axis, one of said arms being substantially longer than the other, the extremities of the arm being bent up to provide driving lugs flanked by supporting shoulders all of which lie in a common plane normal to the shaft axis, the

9

driving lugs being received in the slots in the piece of insulating material; the reaction of the spring fingers against the resistance element and collector ring holding the piece of insulating material against the supporting shoulders, and the insulating shield providing insulation between the driving lugs and the contactor.

9. In a variable resistor having a base of insulating material, a flat arcuate resistance element on one side of the base, a collector ring on the same side of the base concentrically surrounded by the arcuate resistance element, and a contactor having spring contact fingers to traverse the resistance element and the collector ring, means for mounting and driving the contactor, comprising: a shaft constrained to rotation about an axis perpendicular to the base and with which axis the resistance element and collector ring are concentric; a contactor driving member fixed to the shaft and radiating therefrom with one side of the driving member facing and overlying the base; thrust bearing means defining the

5

10

10

axial position of the shaft and the contactor driving member with respect to the base; and means mounting the contactor on said driving member at said side thereof which faces the base and with the spring contact fingers of the contactor in position to traverse the resistance element and the collector ring, said contactor mounting means so locating the contactor on the driving member that the extremities of all of its spring contact fingers lie at the same side of the shaft axis.
